UNITED STATES PATENT OFFICE

167,495

FRONT FOR SUNGLASSES OR THE LIKE

Jack Bloch, Leominster, Mass., assignor to Foster Grant Co., Inc., Leominster, Mass., a corporation of Massachusetts

Application April 25, 1952, Serial No. 19,483

Term of patent 14 years

(Cl. D57—1)

To all whom it may concern:

Be it known, that I, Jack Bloch, a citizen of the United States, residing at Leominster, Worcester county and State of Massachusetts, have invented a new, original, and ornamental Design for a Front for Sunglasses or the like, of which the following is a specification, reference being had to the accompanying drawings, forming part thereof, in which:

Fig. 1 is a face view of a front for sunglasses, showing my new design;

Fig. 2 is a top plan view thereof; and

Fig. 3 is a side view.

The dominant features of the design are shown in full lines in the drawing.

I claim:

The ornamental design for a front for sunglasses or the like, substantially as shown and described.

JACK BLOCH.
